United States Patent Office

Des. 184,348
Patented Feb. 3, 1959

184,348

WHEEL COVER

Paul W. Gillan, Detroit, Mich., assignor to General Motors Corporation, Detroit, Mich., a corporation of Delaware

Application February 17, 1958, Serial No. 49,685

Term of patent 3½ years

(Cl. D14—30)

I claim:

The ornamental design for a wheel cover, substantially as shown.
